United States Patent

Des. 235,285
Patented June 10, 1975

235,285

COMBINED DESK AND FOOTREST UNIT

Henry W. Dawson, 338 10th St. NW.,
Charlottesville, Va. 22901

Filed Sept. 17, 1973, Ser. No. 397,628

Term of patent 14 years

Int. Cl. D6—05

U.S. Cl. D6—42

Fig-2

FIG. 1 is a perspective view of a combined desk and footrest unit, embodying my new design, viewed from the front and right side thereof;

FIG. 2 is a top plan view thereof;

FIG. 3 is a side elevation thereof viewed from the left side of a combined desk and footrest unit;

FIG. 4 is a front elevation view thereof; and

FIG. 5 is a rear elevation thereof.

I claim:

The ornamental design for a combined desk and footrest unit, as shown and described.
